SHEET-END INDICATOR AND SPACE
COUNTER FOR PRINTING MACHINES

Paul F. Guerin, Paris, France

Application February 18, 1950, Serial No. 144,939

14 Claims. (Cl. 197—189)

1

My invention is concerned with a sheet-end indicator and line or space counter to be used generally on all machines for printing sheets of variable lengths when the sheet is driven by a cylinder, and in particular on typewriting machines.

Various kinds of sheet-end indicators have been proposed for warning the operator of the approaching end of the sheet of paper being typed upon. Some of these indicators warn the operator by a single signal, for example the appearance of a red dot in a visor, of the approaching end of the sheet. Such indicators have the great disadvantage of not enabling the operator, within a sufficiently large range (for example, twenty single-space lines), to ascertain the exact position of any line in relation to the approaching end of the sheet.

Some counters have been proposed which provide within a certain range, a continuous system for counting the number of lines remaining available until the end of the sheet is reached. In spite of the desirability of having counters or indicators of this type, typewriters now in commercial use are, to the best of my knowledge, still not provided with them. This may be due to the fact that this type of indicator presents a certain degree of complexity, but also, and more likely, this may be due to the absence of means providing for the free and absolutely unimpeded movement of the sheet or sheets of paper during a return or reverse movement.

In a proposed form of counting indicator of this type, the mechanism is driven by a combination of the movements of the paper and of the platen, the movement of the paper being transmitted to a roller which presses the sheet or sheets against the guide plate of the typewriter. When the paper has passed under the roller it is an essential condition of the functioning of that counter that the roller remains braked by pressing upon the guide plate. However, when the operator reverses the movement of the platen for making a correction on the sheet, or for any other purposes, the presence of the roller and its pressure on the guide plate is likely to prevent the free reverse movement of the paper. This is a particularly important obstacle to the return of thin and flexible sheets of paper for re-engagement under the roller and to the driving of the roller by the reverse movement of the sheets.

The primary objects of my invention, among others, are to provide a wide range of action in counting in both directions, simplicity of construction, ease of adaptation in typewriters and

2

other similar machines and automatic operation, and to provide a space or line counter driven by the platen alone during all reverse movements of the sheet or sheets of paper. This last feature permits the use of a mechanism responsive to changes in the direction of rotation of the platen, the purpose of which is to disengage the roller driven by the sheet being printed and to hold it removed therefrom as long as the reverse movement of the paper lasts. The roller is therefore held in a position where it cannot hamper the reverse movement of the sheet or sheets, and I provide mechanism adapted to return the roller to its former position when the platen and the paper are again moved in a forward direction.

In order to accomplish certain of these functions I provide for a single means for accomplishing a locking action on the mechanism driven by the sheet and roller instead of relying upon the braking action of the roller to effect operation of the counting mechanism per se to count the lines or spaces remaining on the sheet after the sheet has moved from under the roller. This locking action, as will be seen in the following description of the movements of the apparatus, allows a succession of engagements and disengagements of the roller to take place at each change in the direction of rotation of the platen and of the sheet without interfering with the counting operation.

The relative simplicity and small space occupied by my counting mechanism is obtained by means of using only one differential gear train and by the relatively simple means adopted to effect the automatic return of the counter to its initial or starting position when the operator has reached the end of the sheet.

In general, the counting and indicating mechanism of my invention includes a counting means and means responsive to the rotation of the cylinder or platen of a printing machine and to a means such as a roller actuated by the movement of a sheet of paper moving over the cylinder and being printed upon, said mechanism including means for effecting the following operations or conditions:

- (1) preventing the operation of the counting means while the mechanism is driven in a forward direction both by the cylinder and by the roller actuated by the sheet, as long as the sheet is engaged by the roller;
- (2) beginning the operation of the counting means as the sheet moves out of engagement with the roller previously actuated thereby during forward movement;
- (3) automatically resetting the counting means

to its starting position as the approaching end of the sheet thereafter reaches a preselected point prior to being removed from the machine;

(4) operating the counting means in reverse when the operator of the machine turns the cylinder in reverse and moves the sheet backward until it reaches the point where the counter started to count during the forward movement of the sheet; and

(5) preventing the operation of the counting means during any further backward movement of the end of the sheet beyond the point referred to in (4).

In the preferred form of counting mechanism according to my invention, I provide means for normally maintaining the roller under some tension against the paper guide plate so the paper passing between the roller and guide plate will rotate the roller, and, through associated means, operate the part of the mechanism referred to above. In this construction I advantageously mount the roller on a pivoted frame and provide means directly responsive to reverse rotation of the cylinder or platen for swinging the roller away from the sheet or sheets of paper on the guide plate.

My indicating and counting mechanism also advantageously comprises a differential gear train including a pair of parallel bevel gears of equal diameter meshing with an intervening pinion gear. Means is provided for driving one of the bevel gears from the cylinder or platen and means is provided for driving the other bevel gear from the roller when it is engaging the paper on the guide plate in the printing machine. These means are arranged so that the bevel gears are driven at the same rate and in opposite directions during the operation of the typewriter while the paper is under the roller. In this operation the pinion gear merely rotates in place. After the paper is moved from under the roller, however, it will no longer rotate and therefore the pinion gear will be displaced. I therefore advantageously provide a shaft axially of the bevel gears having a fixed radially-extending arm serving as an axle on which the pinion gear is mounted. When the pinion gear is displaced, it rotates the shaft extending through the bevel gears and through suitable mechanism operates the counting means to count the lines or spaces remaining on the sheet. In my apparatus I provide means operative upon the initial movement of said shaft for locking the bevel gear previously driven by the roller.

The preferred form of mechanism also includes means for automatically returning the pinion gear and the counter to its starting or initial position. One form of such construction comprises means operatively associated with the pinion gear axle for disconnecting the driving connection between the cylinder or platen and its bevel gear, means for moving the pinion gear to its initial position, and means operative upon return of the pinion gear to its starting position for reconnecting the cylinder with the bevel gear associated therewith.

My improved sheet-end indicator and counter mechanism may be provided as an attachment for typewriters or other machines, or as a regular part of a typewriter or other mechanism. In this application I illustrate and describe one structural form embodying the features of my invention, it being understood that other structural forms thereof may be made. The detailed features of the invention are described herein in

connection with the accompanying drawings forming a part of this application.

In the drawings:

Fig. 1 is a broken front elevational view of the upper front portion of a typewriter showing the indicator mechanism of my invention attached thereto.

Fig. 2 is a broken sectional view on an enlarged scale taken on the line 2—2 of Fig. 1.

Fig. 3 is a front elevational view partly in section, taken on the irregular line 3—3 of Fig. 2.

Fig. 4 is a broken view similar to that of Fig. 2 showing the arrangement of the means for disconnecting the driving connection between the typewriter platen and the indicator mechanism.

Fig. 5 is a broken vertical sectional view taken on the line 5—5 of Fig. 4.

Fig. 6 is a broken detailed view of a part of the mechanism shown in Figs. 4 and 5 taken on the line 6—6 of Fig. 5.

Fig. 7 is a broken vertical sectional view showing a part of the mechanism of Fig. 2 in a different stage of operation.

Fig. 8 is a view similar to Fig. 5 showing a changed position for certain of the elements.

Fig. 9 is a view similar to that of Fig. 6 showing a changed position for certain of the elements.

Fig. 10 is an elevational view showing a modified form of driving means associated with a cylinder or platen.

Fig. 11 is a broken sectional view taken on the line 11—11 of Fig. 10.

Fig. 1 of the drawings shows my improved sheet-end indicator and counter 15 as an attachment applied to the right-hand side of a typewriter of conventional design including a cylinder or platen 16 mounted in a carriage frame 17 and having a cylinder knob 18. Also shown is the paper guide plate 19 which extends around the back and under-portion of the cylinder 16. A sheet of paper 20 is shown in the typewriter.

The counting mechanism is operatively connected to the platen by providing on the right-hand end of the cylinder a gear wheel 21 meshing with a small gear wheel 22 carried thereon and adapted to rotate a square shaft 23 extending across the typewriter carriage and having its ends rotatably mounted in bearings 24 in the side frame members of the carriage. The square shaft 23 extends through the lower portion of the counting mechanism 15 and supports the front portion of a casing 25. The shaft 23 operates parts of the mechanism 15 by means of gear wheels carried by the shaft and described in detail hereinafter. Another portion of the mechanism 15 is operated by a roller 26 which normally presses against the sheet of paper 20 and is rotated by the movement of the paper during a portion of the normal typing operation. The casing 25 carries a dial housing 27 having a window through which the operator may observe the number of remaining spaces or the lines remaining to be typed on the sheet 20.

From the showing in Fig. 2 it will be noted that the casing 25 is secured to the upper portion of the guide plate 19 by a member 28 which engages both the inner and the outer portions of the guide plate and which is slidable thereon so that the mechanism 15 may be slid along the square shaft 23 and the guide plate 19 to position the roller 26 on the marginal portion of the sheet 20 to the extent desired, according to the width of the paper to be used in the typewriter.

Referring to Figs. 2 and 3 of the drawings, the

central portion of the indicator mechanism includes a rotatable shaft 29 mounted in end bearings carried by the side walls of the casing 25. This shaft is parallel to the square shaft 23 and supports a rigid swing frame on which the roller 26 is mounted for rotation, this frame including a pair of spaced links 30 and 31 rotatable with respect to the shaft 29 and carrying in their outer ends a rotatable shaft 32 on one end of which the roller 26 is fixed.

The shaft 29 also carries a differential gear system including a pair of parallel bevel gears 33 and 34 of equal diameter which have peripheral gear teeth and inner bevel gear teeth, the latter meshing with a satellite or pinion gear 35 which is rotatably mounted on a shaft or arm 36 fixed to the shaft 29. The peripheral gear teeth of the gear 34 mesh with the gear teeth of a gear 37 fixed to the shaft 32 so that rotation of the roller 26 causes rotation of the gears 37, 34 and 35. The peripheral gear teeth of the gear 33 mesh with the gear teeth of a small gear 38 carried on the shaft 23, as shown in Fig. 4, and described more in detail hereinafter.

The means for controlling the swinging movements of the roller 26, and particularly for retracting the roller automatically, are shown in Figs. 2 and 3 of the drawings in connection with the parallel axles or shafts 29 and 32. At the right side of the mechanism a triangular frame is provided at a right angle to the supporting frame, in which the link 31 is the diagonal member, a link 39 is the horizontal member, and a link 40 is a vertical member. The links 39 and 40 have ends respectively carried on the shafts 32 and 29 and in which such shafts are rotatable. The other ends of the links 39 and 40 are loosely clamped together by a screw or rivet 41, the shank of which is slidable laterally against a spring 42 in a slot in the link 39. The links 39 and 40 may be slotted and tubular so as to suitably retain the springs as shown. The link 40 carries two springs 43 and 44 bearing against a movable member pivoted to one end of a lever 45 which is pivoted to the side of the casing 25 by a pivot member 46. The lower end of the lever 45 engages in a star wheel 47 mounted for rotation on and with the square shaft 23.

When the cylinder 16 is reversed by the operator, the star wheel 47 rocks the lever 45 on its pivot and quickly swings the roller 26 on its supporting frame away from the guide plate 19 so that the roller does not interfere with the retraction of the sheet or sheets of paper in the typewriter. When the typewriter is operated under normal conditions, the star wheel 47 rotates counter-clockwise and urges the lower end of the lever 40 to the right in Fig. 2 and thereby maintains a tension on the spring 42 which urges the roller 26 resiliently against the paper or the guide plate 19.

The roller 26 is of such diameter and the various gears are correlated with respect to each other and the diameter of the cylinder 16 so that while the parallel gears 33 and 34 are being respectively driven by the platen and the roller, they will rotate in opposite directions and at the same rate so that the satellite gear 35 will rotate in place without moving through an arc. However, the mechanism is arranged so that when the end of the paper, such as the sheet 20, in the normal course of a typing operation, passes under the roller 26, the roller stops rotation and also stops rotation of the gear 34. The satellite gear 35 is therefore moved through an arc by the

subsequent rotation of the gear 33. The shaft 36 is moved at the same time and turns the axle or shaft 29. This movement is relied upon for rotating an indicator or counting dial 48 in the housing 27. I therefore provide a disc-like cam wheel 49 to the right of the gear wheel 34 in Fig. 3 and fix it to the axle or shaft 29 for rotation thereby. The right face of this wheel 49 carries an integral surface ring gear 50 which meshes with a small pinion gear 51 fixed to a rotatable sleeve 52 to which the indicator dial 48 is fixed. The sleeve 52 is mounted on a fixed shaft 53 which extends through the pinion gear 51 and which has a bearing mounted around the shaft or axle 29 and includes an integral portion extending beyond the shaft 29. As the satellite gear 35 moves clockwise in Fig. 2, it rotates the disc wheel 49 clockwise and also rotates the pinion gear 51 and sleeve 52, the latter of which has a bearing in the casing 25.

The disc-like cam wheel 49 is provided with a peripheral cam surface of large diameter, extending counter-clockwise through 180° or more from the shoulder 54, normally engaged by a roller 55 carried on an arm 56 mounted on a shaft 57. The arm 56 is integral with a dog 58 extending over the peripheral cogs of the gear wheel 34. As soon as the satellite gear 35 and its axle commence to move through an arc, the shoulder 54 on the cam wheel 49 is moved against the roller 55 and engages the dog 58 in the gear teeth of the wheel 34, thereby locking that wheel against further rotation and thus insuring accurate counting by the mechanism and permitting the free swinging of the roller during the counting period. The locking of the gear wheel 34 during the counting period dispenses with the necessity of relying upon the presence and uncertainty of the braking action of the roller 26 and allows the roller to be retracted at will when the cylinder and paper are reversed.

It is only necessary that the satellite gear 34 and the cam wheel 49 move through an arc of 180° or thereabouts in order to count and indicate the necessary number of lines which are displayed on the dial 48. As the cam wheel 49 moves through that arc, it rotates against the biasing action of a tension spring 59 having the right end shown in Fig. 2 attached to the wheel, while the left end is attached to the fixed shaft 53. The spring 59 is mounted in a circular shaped housing 60 attached to the shaft 59. After the cam wheel has been rotated through an arc of 180°, the wheel 33 is released for free rotation and the spring 59 rotates the cam wheel counter-clockwise and restores the dial 48, the cam wheel 49 and the satellite gear 35 to their initial or starting position. As this occurs, the roller 55 passes over the shoulder 54 and unlocks the wheel 34.

The foregoing operations described in connection with the movement of the satellite gear involve other correlated actions for disconnecting and reconnecting the bevel gear 33 with respect to rotation by the cylinder 16.

As shown in Figs. 4, 5 and 6, the bevel gear 33 is driven by the gear 38 which is rotatably mounted on the square shaft 23, the gear 38 being kept in mesh with the gear 33 and driven by a gear 61 integral with a sleeve 62 which fits shaft 23 and which is driven thereby. The gears 38 and 61 have intermeshing facing gear teeth which when engaged provide a positive drive for the gear 38. The sleeve 62 and the gear 61 are urged toward the gear 38 by a light spring 63 bearing against

a stop 64 mounted on the shaft 23. Means is provided for shifting the sleeve 62 to the right in Fig. 4 to take the gear 61 out of mesh with the gear 38 and thereby discontinue the rotation of the gear 33 by the cylinder.

The mechanism for reciprocating the gear 61 and its sleeve 62 is shown in Figs. 4, 5 and 6 and includes an annular channel on the sleeve 62 formed by the surface 65 of the gear 61 and a ring flange 66 integral with the sleeve 62. A roller 67 carried on a pivoted arm or lever 68 operates between the surface 65 and the flange 66, the opposite end of the arm 68 being pivoted to a support 69 (Fig. 5) carried by the front of the casing 25. The lever 68 comprises a part of a snap acting mechanism actuated by a spring 70 under tension, one end of which is attached at the free end of the lever 68 while its other end is attached to the front of the casing 25. When the free end of the lever 68 is moved across the center line extending through its point of attachment to the support 69 and the point of attachment of the spring 70 to the casing, the free end of the lever and the roller 67 moves quickly in that direction to shift the sleeve 62 and its gear 61.

In accordance with the present invention, this shifting operation is effected by cam members 71 and 72 attached to the opposite ends of the shaft 36, the cam member 71 being attached to the end of the shaft which extends beyond the satellite gear 35.

In a counting operation as described above, the satellite gear 35 moves clockwise as shown in Fig. 5, and as the cam 71 approaches the position of the sleeve 62 (Figs. 6 and 8) the sloping front edge 73 of the cam engages a roller 74 mounted above the roller 67 on the trip mechanism, and moves the free end of the lever or arm 68 to the right in Fig. 4 until the roller 71 moves across the center line and engages the flange 66. At that instant the snap acting trip mechanism takes the gear 61 out of engagement with the gear 38, thereby permitting free rotation of the differential gear 33 as well as the gear 38, by the action of the spring 59 which returns the satellite gear 35 to its initial or starting position.

As the satellite gear 35 approaches its initial or starting position at the upper part of the mechanism, the opposite end of the shaft 36 carrying the cam 72 approaches the sleeve 62 (Fig. 9) and the sloping surface 75 of the cam 72 engages the roller 74 to move it and the free end of the arm 68 to the left in Figs. 4 and 9, across the center line position, whereupon the roller 67 engages the surface 65 and slides the sleeve 62 along the shaft 23 so that the gear 61 is almost instantly put in mesh with the gear 38. At the time the gears 38 and 61 mesh, further movement of the shaft 36 in that direction is stopped. When this position of the shaft 36 is approached its upper end above the gear 35 moves into engagement with a friction spring 76 attached to the casing 25 which retains the gear 35 in a steady position ready for the beginning of another counting or measuring operation.

When the reverse movement takes place outside of the counting range, and while the spring 76 is holding the gear 35 in place, (1) the roller 26 is lifted off the sheet, (2) the sheet moves back up the guide plate, (3) the gear 35 merely rotates in place since it is driven by the cylinder and the differential gear 33, and (4) the roller 26 being disengaged, the gear 34 and the roller 26 are rotated freely by the satellite gear 35.

Figs. 5 and 7 show the position of the gear 35

and the shaft 36, together with the cams 71 and 72 attached thereto just after the start of a counting operation. At this time, the dog 58 is engaged in the gear 34. A torsional spring 57a is mounted on the shaft 57 for normally holding the dog 58 away from the gear 34 and causes the roller 55 to move down over the shoulder 54 when the satellite gear 35 returns to its initial position after carrying out a counting operation.

Figs. 6 and 8 of the drawings show the positions of the shaft 36 and its associated elements at a point near the end of a counting operation. The cam 71 is preferably arranged with respect to the trip mechanism operated thereby so that as this cam approaches the roller 74, the actuation of the cylinder through one space will trip the mechanism and disconnect the gear wheel 33 from rotation by the square shaft 23.

The counting may be carried out in different ways for different machines. The initial position of the counter in the illustrative example is indicated in Fig. 1 as corresponding to line "20," as shown in the window of the housing 27. This corresponds to a situation in which there are twenty lines or spaces remaining on the sheet of paper and as the counting starts the indicator will show the numbers successively from "20" down to zero, so that the operator will know at a glance exactly how many lines or spaces remain upon the sheet of paper being printed upon.

When the operator desires to commence a typing operation, the cylinder of the machine is given a slight turn in reverse which instantly lifts the roller 26 and permits the free movement of the paper into position in back of and under the roller. Thereafter, when the operator rotates the paper into typing position with the cylinder the roller 26 is instantly brought against the paper, pressing it against the guide plate 19. Regardless of the length of the sheet of paper employed, the indicator dial will show the number "20" until the end of the sheet of paper passes from under the roller 26. At this point the counting operation proceeds in the manner described above.

The mechanism of the present invention is designed to be automatic to the greatest extent possible, so that little or no attention will be required by the operator. If desired, however, the front of the casing may carry a small slide or knob which is spring-biased in one direction and which may be actuated instantly by the operator to trip the snap acting mechanism for releasing the gear wheel 33. This, however, is not regarded as necessary, although it may be possible that an operator, desiring to do so, may remove a typed sheet from the machine before the counting mechanism has progressed through to zero to trip the snap acting means. The mechanism may be operated to the trip point by merely rotating the cylinder forward. During ordinary operation, however, even though the page is not typed to the end, the rotation of the cylinder to remove the paper will carry the counting to the end and trip the snap acting mechanism to release the gear wheel 33.

In order to simplify the showing in the drawings, certain standard elements which would be normally included are not shown. For example, it will be understood that the gear wheels 33 and 34 carried on the shaft 29 will be held in place by suitable spacer collars and the same is true of other elements mounted on this shaft and the shaft carrying the roller 36. The collars between the gear wheels 33 and 34, of course, will serve

as spacers and be fixed to the shaft 29 while the gears themselves are free to rotate thereon. Furthermore, the swing arms carrying the shaft on which the roller 26 is mounted will carry relatively long spacer collars which will contribute to the rigidity of the shaft and hold the various elements in the positions shown in the drawings.

Figs. 10 and 11 show a modified form of counting and indicating mechanism which is the same as that described above, except for the means employed for driving it from the cylinder or platen. In these views the elements shown corresponding to those described above are indicated by the same reference characters followed by the letter *a*.

The casing 25a shown in Fig. 10 may be secured to the carriage by a clamp or other suitable means, not shown, while the square shaft 23a is short and is rotatably mounted in bearings in opposite sides of the casing. One end of this shaft extends to one side of the casing and has fixed thereto a roller 77 of polygonal cross-section mounted in engagement with the surface of the cylinder 16a and driven thereby. Each flat surface 78 of the roller 77 may represent a single space movement of the cylinder, or the width of each surface 78 may correspond to the distance through which the periphery of the cylinder moves in one step. The polygonal shape of the roller 77 insures a more positive drive than if it were cylindrical.

The roller 77, as well as the other roller used with either form of the device is advantageously made of suitable rubber material such as that used for making the cylinder or platen.

The device or mechanism forming the subject of the present invention has been described in connection with its preferred use with typewriters and other printing machines to which it is attachable. It is to be understood, however, that the mechanism may have other uses for counting and measuring spaces or distances and for showing to an operator the position or stage of operation of a machine or device when it approaches a critical or important condition.

While specific structures have been shown and described for various parts of the apparatus of the present invention, it is to be understood that other equivalent or alternative structures may be employed. For example, instead of having the shaft 36, a disc may be used which is fixed to the shaft extending through the gear wheels 33 and 34, and other connections may be made for operating the indicator and counting means. The indicator may also have a different form and may be operated more directly by the movement of the gear 35 around the gears 33 and 34. Other changes may be made as contemplated within the scope of the appended claims.

I claim:

1. In a sheet-end indicator and space counting mechanism for printing machines having a cylinder and a guide plate cooperating therewith, a roller biased toward the guide plate and adapted to engage and bear against the surface of a sheet of paper passing over said plate and around said cylinder, said roller being adapted to be rotated by the movement of the paper over the surface of the plate, an indicating and counting means, a control mechanism operatively associated with the cylinder for moving the indicating means in one direction as the cylinder is rotated during a typing operation, means operatively associated with the roller and said con-

trol mechanism for annulling the action of the cylinder and said control mechanism to move the indicating means during the time the roller is rotated by the sheet of paper, and means actuated by the cylinder and responsive to its reverse rotation for disengaging the roller from the sheet of paper, whereby the sheet of paper is freely movable along said plate away from the cylinder during the reverse rotation of the cylinder.

2. A mechanism as claimed in claim 1 in which said control mechanism comprises two parallel gear wheels of equal diameter and a pinion gear meshing therewith, said gear wheels being respectively connected for rotation by the cylinder and roller, and means actuated by the pinion gear for moving the indicating means.

3. A mechanism as claimed in claim 2 characterized by including means operatively associated with the pinion gear for locking the gear wheel connected with the roller.

4. A mechanism as claimed in claim 3 characterized by including a first shaft extending axially through the gear wheels and upon which said wheels are rotatable, a second shaft extending from the pinion gear and fixed to the first shaft, and means actuated by the first shaft for moving the indicating means.

5. A mechanism as claimed in claim 4, characterized by including a cam wheel fixed to the first shaft outside said gear wheel connected to the roller, and means actuated by the cam wheel for locking said gear wheel when said pinion gear is moved to in turn move the indicating means.

6. A mechanism as claimed in claim 5, characterized by including means actuated upon movement of said pinion gear through a predetermined arc for disconnecting the cylinder from the gear wheel connected thereto, and means for rotating said disconnected gear wheel to return the pinion gear to its initial position.

7. A mechanism as claimed in claim 6, characterized by including means actuated upon movement of said pinion gear to its initial position for reconnecting the cylinder with its gear wheel.

8. In a mechanism of the type described for printing machines having a cylinder and a guide plate cooperating therewith, a roller biased toward the guide plate and adapted to engage and bear against the surface of a sheet of paper passing over said plate and around said cylinder, said roller being adapted to be rotated by the movement of the paper over the surface of the plate, an indicating means, a differential mechanism including two parallel gear wheels of equal diameter meshing with a pinion gear, means for driving one of said wheels by the cylinder for in turn moving the indicating means in one direction as the cylinder is rotated during a typing operation, means operatively associated with the roller for driving the other wheel in the opposite direction at the same rate as the first wheel during the time the roller is rotated by the sheet of paper, means actuated by the pinion gear for moving the indicating means, means responsive to the movement of the pinion gear in one direction around the gear wheels for disconnecting the cylinder from its gear wheel, and means for thereafter returning said pinion gear to its initial position.

9. A mechanism as claimed in claim 8, characterized by including means responsive to the movement of the pinion gear to its initial posi-

11

tion for reconnecting the cylinder with its gear wheel.

10. A mechanism as claimed in claim 8, characterized by including means for automatically moving the roller away from the guide plate in response to the reverse rotation of the platen.

11. A mechanism as claimed in claim 1 in which said control mechanism comprises two parallel gear wheels of equal diameter, a pinion gear meshing therewith, said gear wheels being respectively connected for rotation by the cylinder and the roller, means actuated by the pinion gear for moving the indicating means, and means operatively associated with the pinion gear for locking and unlocking the gear wheel connected with the roller.

12. A mechanism as claimed in claim 1 in which said control mechanism comprises two parallel gear wheels of equal diameter, a shaft extending axially through said gear wheels and upon which they are rotatably mounted, said gear wheels being respectively connected for rotation by the cylinder and roller, a pinion gear meshing with said gear wheels, means interconnecting said pinion gear with said shaft for rotating said shaft, and means actuated by the rotation of said shaft for moving the indicating means.

13. A mechanism of the type described, comprising a roller adapted to engage and bear against the surface of a movable member and be driven thereby, a counting means, a second driving means, a differential mechanism operatively associated with the second driving means for moving the counting means in one direction, means operatively associated with the roller and said differential mechanism for annulling the action of the second driving means and said

12

mechanism to operate the counting means during the time the roller is rotated by the movable member, and means actuated by the second driving means and responsive to its reverse rotation for disengaging the roller from the movable member.

14. A counting device comprising a differential mechanism including a pair of parallel wheels and a satellite wheel engaging said wheels and driven thereby, a counting means actuated by the movement of said wheel around said pair of wheels, a first driving means for revolving one of said pair of wheels, a second driving means for revolving the other of said pair of wheels, means responsive to the braking or stopping of the first driving means for locking the wheel of said pair revolved thereby, whereby operation of the second driving means effects movement of the satellite wheel around said pair of wheels and drives the counting means, means actuated by the movement of the satellite wheel through an arc less than a circle for disconnecting the driving connection between the second driving means and the parallel wheel driven thereby, and means for reversing the rotation of the said parallel wheel and thereby reversing the direction of movement of said satellite wheel.
